UNITED STATES PATENT OFFICE.

JOHN B. TIMBERLAKE, OF JACKSON, MICHIGAN.

PLATE OR PICTURE EASEL.

SPECIFICATION forming part of Letters Patent No. 651,215, dated June 5, 1900.

Application filed October 4, 1895. Serial No. 564,632. (No model.)

To all whom it may concern:

Be it known that I, JOHN B. TIMBERLAKE, a citizen of the United States, residing at Jackson, in the county of Jackson and State of Michigan, have invented certain new and useful Improvements in Plate or Picture Easels, of which the following is a specification, reference being had therein to the accompanying drawings.

- 10 Figure 1 is a front elevation of one form of easel or holder embodying my invention. Fig. 2 is a side elevation of the same, showing a plate supported by the holder or easel. Fig. 3 is a rear view, the plate being represented. 15 Fig. 4 is a side view of another form of holder embodying my invention. Fig. 5 is a front view, Fig. 6 is a side view, and Fig. 7 a rear view, of still another form of the invention, a plate being represented in Fig. 5, but not in 20 Figs. 6 and 7. Figs. 8, 9, and 10 are perspective views showing other forms of the invention; and Fig. 11 is a detail view, enlarged, showing one method of uniting the ends of the wire from which the easels or holders are 25 made.

My invention has for its object to construct a holder for plates, platters, plaques, and similar articles, which are frequently supported upon easels, that shall possess certain features of novel construction which tend to improve the easel or holder, as will be herein-after set forth.

In order to secure the desired steadiness of a support for a plate or round plaque and 35 overcome any tendency to roll, it is important that the supporting side arms of the easel or holder shall be far enough apart to permit the edge of the plate to enter so far between the arms that the weight of the article shall 40 exert a noticeable wedging action downward and laterally against the arms, and in order to insure sufficient rigidity or firmness of resistance to such spreading action with the relatively-light wire which it is desirable to 45 use in the manufacture of such holders I have found that it is important to connect together the arms upon which the article rests at their front ends by means of a link or tie piece which is integral with said arms and to 50 form a bearing or throat to receive the lower edge of the plate or plaque by bending upward the same integral wire to form a throat or bearing between each of the arms and the wire of the cross piece or tie.

In carrying out my invention I prefer to 55 cut the wire of the proper length and commence the operation of bending it into the desired shape at two points which are so far equidistant from its center that the space between the bends shall correspond substantially to the desired distance between the front ends of the side arms. Commencing at such points I bend the wire preferably simultaneously at both points into suitable shape to constitute the feet or bearings B. The wire 60 is bent upward from the feet and formed into suitable shape, preferably a curvilinear shape, to constitute the upper member C of a throat or bearing the lower member of which is the horizontal or side arm D. The free or end 65 portions of the wire are then shaped so as to constitute a rear support for the easel and also a support for the plate or article to be held in rear of the throats or bearings C D.

A represents the central tie or cross piece 70 extending between the front feet or bearings B and operating to hold them and the side arms D from lateral separation under the weight of the article supported upon the 75 holder or easel.

I will now describe the peculiar features 80 which distinguish the several forms of my invention illustrated in the drawings.

In Figs. 1, 2, and 3 it will be observed that the side arms D, against which the edges of 85 the plaque or plate bear, are situated such distance apart as to permit the portion of the edge of the plate between them to extend a noticeable distance below the bearing-points upon the arms D, this being clearly represented in Fig. 3. This, as has been stated, causes the plate, particularly if heavy, to exert a considerable wedging action upon the side bars D, tending to separate them, and the integral cross or tie piece A is for the purpose of preventing the undue separation or spreading of the side arms. It will also be noticed, particularly by reference to Figs. 1 and 2, that the bearings or throats between the upturned member C and the side arms or 90 bearings D are sufficiently raised or lifted above the bearing edges of the feet B to insure the plate being held as just described. In the form of invention being described the wire from which the article is formed is bent 95 into large loops or coils in rear of the side arms D, which constitute the rear feet or bearings for the easel or support, the bearing-

points for these feet being in rear of the portion of the support with which the central part of the plate or plaque engages. The ends of the wire after being bent to form the 5 feet or bearings E are continued backward and upward, so as to constitute the upward extensions F above the side arms D and against which the upper portion of the plate or plaque may rest. I prefer that the upward extensions F should also be arranged in front of the bearing-points of the feet or supports E in order that the center of gravity 10 of the article supported upon the holder may be so far forward as to preclude any danger 15 of the easel tipping over backward. The ends of the wire are turned inward toward each other from the upper ends of the extensions F, and constitute a horizontal connecting-piece G, the ends of the wire being united 20 by a ferrule or sleeve g, (see Fig. 11,) which may be applied in any usual or approved manner.

The form of my invention represented in Fig. 4 differs from that just described in that 25 it lacks the upward extensions F F. The ends of the wire after being formed into the rear feet or bearings E may terminate at about the point e, or the ends of the wire may be bent in toward each other at about the position indicated at e and united as represented 30 in Fig. 11 or otherwise, as preferred. This form of the invention is well adapted for supporting a plate with a moderately-deep bevelled rim or flange.

35 In the form of my invention represented in Figs. 5 to 7, inclusive, the upward extensions F instead of being parallel with each other converge, as shown in Fig. 7. In a form like this it would usually be most desirable to unite the ends of the wire at the apex of the converging extensions F. In this form of the invention it will also be noticed that the throat or bearing between the parts C and D is not situated so far above 45 the bearing points or edges of the forward feet B as in the first-described form of my invention. In this respect it is not so desirable as the form first described, as a plate which is supported thereby, especially if rather 50 small, will not rest firmly upon the side arms D D, but will bear against the surface upon which the easel or support rests and will be liable to roll or rock to a slight extent.

In Figs. 8, 9, and 10 other forms of my invention are described. It is thought, however, that these views need not be described in detail. It will be sufficient to note that in each form of the invention the side bars D, the forward feet or bearings B, the upward 60 continued or extending members C C, which coöperate to form the throat for the edge of the article held, and the cross or tie piece A are integral and that the side arms D, against which the middle portion of the article may 65 rest, are in front of the rear support for the holder.

While I have represented the rear support

of the article as consisting of feet or bearings E E, which are circular in outline, they may be otherwise constructed or arranged, the particular shape and disposition of these feet being a matter which may be left to the taste of the designer or manufacturer. Thus in Fig. 8 I have represented the feet or bearings being of large scroll form, while in Fig. 10 75 they are represented as being circular, but rather small in size, and in this view the portions of the wire N above the bearings or feet E E are represented as converging and being 80 twisted together.

The arrangement and disposition of the cross-tie piece A may be varied without departing from the spirit of my invention. Thus in Figs. 1, 2, 3, 8, 9, and 10 the cross-ties there represented are so disposed as to 85 be in rear of the lower edge of the article supported, while in the form of invention shown in Figs. 5, 6, and 7 the cross-tie piece A lies in front of the article supported.

It will be observed by reference to the several views that the support for the central and upper portions of the plate or article may be variously inclined and disposed without departing from the essential features of my invention.

Having described my invention, what I claim, and desire to secure by Letters Patent, is—

1. A wire support for holding a plate or plaque vertical or inclined edgewise, comprising side arms connected at their front ends by a horizontal tie-piece integral with the side arms, the wire from which the said side arms and horizontal tie-piece are formed being bent downward to form feet or bearings at the front ends of the arms, and bent upward to form rests for the lower edge of the plate, the said rests being situated above or higher than the forward feet and bearings for the arms, the rear feet or bearings for the support and a support for the central portion of the article arranged in front of the rear feet, substantially as set forth.

2. A wire support or holder for a plate or the like, formed of a single piece of wire bent to constitute the cross-tie A, the forward feet or bearings B, B, at the ends of the cross-tie, the upward extensions, C, C, above the feet or bearings, the side arms D, D, there being formed bearings or throats for the edge of the article between the side arms D and the upward extensions C, the rear feet or bearings E, E, and the upward rear extensions F, the bearings or resting-surfaces for the feet E, being in rear of the portion of the support or holder against which the central and upper part of the article rests, substantially as set forth.

In testimony whereof I affix my signature in presence of two witnesses.

JOHN B. TIMBERLAKE.
